Primary Examiner — T Chase Nelson(74) *Attorney, Agent, or Firm* — Banner & Witcoff, Ltd.(57) **CLAIM**

The ornamental design for a shoe with sole having a transparent window, as shown and described.

DESCRIPTION

FIG. 1 is a rear bottom perspective view of a shoe with sole having a transparent window showing my new design;

FIG. 2 is a bottom view thereof;

FIG. 3 is a bottom side perspective view thereof;

FIG. 4 is a side view thereof; and,

FIG. 5 is an opposite side view thereof.

The oblique line shading represents transparency. The broken lines immediately adjacent to the shaded areas define the bounds of the claimed design and form no part thereof. The broken lines showing the remainder of the shoe are for environmental purposes only and form no part of the claimed design.
